UNITED STATES PATENT OFFICE.

NICHOLAS J. SCHLACHTER, OF GETTYSBURG, SOUTH DAKOTA.

SILO.

1,043,034.

Specification of Letter's Patent. Patented Oct. 29, 1912.

Application filed June 15, 1912. Serial No. 703,900.

To all whom it may concern:

Be it known that I, NICHOLAS J. SCHLACHTER, a citizen of the United States, residing at Gettysburg, in the county of Potter and State of South Dakota, have invented certain new and useful Improvements in Silos, of which the following is a specification, reference being had to the accompanying drawings.

This invention comprehends certain new and useful improvements in silos and relates more particularly to the method of building silos of the crib pattern.

The primary object of the invention is to provide a circular silo of this type so constructed as to eliminate the use of bands or hoops for holding the body timbers together.

The invention also aims to provide a silo having a body formed of vertical timbers, the ends of which are oppositely beveled so that the base and cover of said silo will tend to hold the body together.

Another object of the invention is to provide a novel method of fastening silo doors in position.

With these and other objects in view, as shall become apparent as the description proceeds, the invention consists in certain novel constructions and arrangement of parts as I shall hereinafter fully describe and claim.

For a complete understanding of my invention, reference is to be had to the following description and accompanying drawing in which—

Figure 1 is a side elevation of my improved silo. Fig. 2 is a transverse sectional view taken on the plane of line 2—2 of Fig. 1. Fig. 3 is a longitudinal sectional view taken through one of the door openings and showing the manner in which the door is secured in position and also showing how the roof is supported and Fig. 4 is a sectional view showing a portion of the foundation and one of the timbers supported thereon.

Referring to the drawing by numerals, 1 designates the base or foundation of the silo, 2 the body, and 3 the roof thereof. The body 2 is circular and formed by the vertical timbers 4, which are rectangular in cross-section and arranged with their vertical longitudinal bisecting planes in radial alignment. The inner lateral edges of each timber 55 contact with the adjacent lateral edges of the adjoining timbers, which arrangement pro-

vides a continuous interior wall. The side faces 5 of the timbers 4 form outwardly extending dihedral angles which are filled with a suitable packing 6 such as cement or other waterproof material. It is not necessary that this packing should entirely fill the openings between the faces of the timbers but may extend inwardly only a short distance. The inner contacting edges of the timbers 4 are held together by the spikes 7, each spike extending through one timber and partly through an adjoining timber.

The lower ends of the timbers 4 are beveled downwardly and inwardly and rest upon the inclined surface 8 of the foundation 1. This inclined surface 8 is wider than the timbers 4 so that they may work inwardly a slight distance but are prevented from working outwardly by the vertical wall 9. The upper ends of the timbers 4 are beveled downwardly and outwardly and support the conical roof 3. It will be seen that the weight of this roof also tends to draw the body members or timbers 4 inwardly.

A plurality of aligned openings 10 are formed in the body 2 by cutting away at intervals portions of a number of successive timbers 4. These openings provide entrances into the silo and are normally closed by the doors 11 which may be constructed in any suitable manner. Fasteners 12 are pivotally secured on a line with the vertical centers of the doors by the bolts 13. Each fastener is formed with an opening in its outer end which receives a pintle 14 that passes through spaced ears formed on the bolt 13. The ends of the fasteners 12 engage over the cross bars 15 which are secured transversely of the openings 10. The ends of each cross bar are secured in mortises or notches formed in the outer edges of the uncut timbers forming the said walls of the openings 10. It will be seen that the weight of each door, the leverage of the clutch or fastener 12 and the pressure of the contents of the silo all combine and tend to hold the door securely in position over the openings 10 in close contact with the interior of the silo. It will be seen that this construction of silo door and the manner of fastening it in position is such as to provide a continuous and essentially unbroken interior surface for the silo which will be free from any obstacles that would tend to catch the ensilage and form air spaces. Each door may

be easily opened by moving same vertically a sufficient distance to relieve the fastener 12 of any pressure after which said fastener may be removed from the cross bar 15.

5 From the foregoing description in connection with the accompanying drawing it will be seen that I have provided a silo construction which dispenses entirely with the use of hoops or bands to hold the body timbers together. The weight of the roof 3 resting upon the timbers 4 tends to draw them inwardly and this tendency acting in conjunction with the beveled wall 8 in the foundation 1 effectually overcomes the outward pressure due to the contents of the silo. The packing material 6 also aids materially in forming a firm and rigid body.

10 The fastening means which I have shown for holding the doors in position is very simple, easily applied and easily operated.

15 It will be noticed that the fasteners 12 are secured below the horizontal centers of the doors. This is purposely arranged to prevent the lower ends of the doors swinging inwardly and to allow the doors to be easily opened.

20 While I have shown a preferred embodiment of my invention, it is to be understood that I do not wish to be limited to the exact construction and arrangement herein shown,

but may make such modifications as fall in the scope and spirit of the invention, as defined by the appended claim.

What I claim is:

25 A silo having a circular body comprising a plurality of vertical timbers, rectangular in cross section and arranged radially with respect to the longitudinal center of the body, the inner lateral edges contacting whereby a continuous interior wall is formed, the 30 upper ends of said timbers being inclined downwardly and outwardly, a conical roof supported upon said downwardly and outwardly inclined timbers, the lower ends of said timbers being inclined downwardly and 35 inwardly, and a base formed with a circular wall which is inclined downwardly and inwardly, said wall being of a greater width than the length of the inclined lower ends of the timbers, whereby said timbers will, 40 because of their weight and the weight of the conical roof, be crowded inwardly to cause their inner lateral edges to bind tightly against one another.

45 In testimony whereof I hereunto affix my 45 signature in the presence of two witnesses.

NICHOLAS J. SCHLACHTER.
